UNITED STATES PATENT OFFICE.

DANA E. HARDING, OF ARLINGTON, MASSACHUSETTS, ASSIGNOR TO HARDING ENGINEERING COMPANY, OF EAST BOSTON, MASSACHUSETTS, A CORPORATION OF MASSACHUSETTS.

ROTARY STAKING MACHINE.

Application filed August 8, 1925. Serial No. 48,945.

My present invention relates to leather working machines, and more particularly to an improved staking machine.

An important operation in the manufacture and preparation of leather from skins or hides is that operation known as staking. This operation consists in flexing the leather between two elements and between which the leather is drawn, the idea being to rapidly 5 flex the leather so as to make the same pliable. This operation is performed prior to either the glazing or boarding operation and is one of the operations that causes more trouble in the leather industry than almost 10 any other single operation. The prior machines for performing this operation consist primarily of a rapidly reciprocating crosshead on which is pivotally mounted a lever carrying at its end a member that is 15 associated with a like member on the crosshead. The operator stands in front of the crosshead which moves towards him and in the forward movement of the lever, carrying 20 the member, lifts the member upward so that 25 the lever and crosshead form an open jaw into which the sheet of leather is placed. When the crosshead with attached lever has 30 reached its foremost position or the position nearest the operator, the lever pivots, bringing 35 the member thereon into association with the corresponding member on the crosshead and the crosshead then moves backward. The operator holds, with his hands or with 40 his hands and body combined, the leather 45 against the front of the machine and prevents the same from being pulled rearwardly of the machine by the flexing elements carried on the crosshead and lever. This 50 operation is very tiring and it is impossible 55 for an operator to work the machine to anywhere near its capacity for a full day. The 60 machine is dangerous and numerous accidents have occurred, both from the crosshead 65 striking the operator and from the 70 muscle strain that necessarily takes place 75 when the operator is working on a heavy 80 piece of leather.

My present invention has been designed to 85 overcome the objections in prior apparatus 90 and to substitute as far as is possible 95

mechanical means for the human element heretofore considered necessary. The prior machines have been of the reciprocating type and, as such, they vibrate excessively and transmit the vibrations to the building 55 in which they are located to such an extent that the buildings have to be strongly built in the first instance and have frequently to be shored up and strengthened. My present invention obviates this difficulty by substituting for the reciprocating crosshead a cylindrical member carrying at intervals 60 along its periphery members that cooperate with devices arranged at intervals on an endless chain and on which the leather to 65 be staked is placed. In combination with such means I provide an automatic mechanical holding device for holding the leather in position while the same is being operated on by the staking device, this movement being 70 such that the leather is held only when the staking or flexing elements are in association with each other.

The principal object of my invention, therefore, is an improved staking machine 75 of the rotary type.

Another object of the invention is an improved staking machine in which the leather being worked on is mechanically held during 80 the staking operation.

Other objects and features of the construction and arrangement of parts comprising my invention will appear as the description of the invention progresses.

In the accompanying drawings illustrating 85 the preferred embodiment of my invention:

Fig. 1 is a side elevation;

Fig. 2 is an end elevation;

Fig. 3 is an enlarged view of a portion of 90 the apparatus shown in Fig. 1, and

Fig. 4 is a sectional elevation on the line 4-4 of Fig. 3.

Referring to the drawings, 10 designates a base on which is secured at one end thereof 95 a pair of spaced upwardly and forwardly inclined pedestals 11. At the upper end of the pedestals 11 and in alignment with each other are bearings 12 and in these bearings is rotatably mounted a drive shaft 13. On the 100

drive shaft 13 are the usual tight and loose pulleys 14 and 15 respectively, and on the ends of the shaft are secured collars 16 that prevent longitudinal movement of the shaft 13 in the bearings 12.

Secured to the shaft 13 between the pedestals 11 is a hub 17 provided with a plurality of radially extending arms 18, and connecting the outer ends of the arms and 10 forming the rim of a wheel are the members 19. Secured to the rim of the wheel at the junction point of the arms 18 and 19 by bolts 20 are members 21 provided on opposite faces with spaced members 22.

Secured to the base 10 in advance of the pedestals 11 are pedestals 23, these pedestals being spaced apart from each other, and secured to each of the pedestals in any convenient manner and extending rearwardly 15 therefrom are frame members 24. These frame members 24 extend rearwardly as far as the rear end of the pedestals 11 and are secured to the inner faces of such pedestals in any convenient or usual manner. On the 20 inner opposing faces of the frames 24 are formed rectangular grooves 25, such grooves forming an arcuate path of which the shaft 12 is substantially the center, as clearly seen in Fig. 1. Mounted within the rectangular grooves 25 for rolling or sliding movement therein are rollers 26 on the ends of shafts 27 forming the cross bars of an endless belt. This endless belt includes a plurality of links 28 and 29, the number of links 25 being less than the number of links 28 in any desired proportion, and I have, for convenience, shown but two of such links. The links 29 are T-shaped in elevation, as clearly 30 shown in Fig. 3, and in the T-shaped portion 35 is secured a shaft 30. On such shaft is rotatably mounted a roller 31. This roller 31 is of such diameter that, when a sheet of leather or other material 32 to be staked is placed thereon, as shown in Fig. 3, the 40 spaced members 22 will crowd down on and exert considerable pressure on such leather and against the rolls 31.

Secured to the shaft 13 is a sprocket 33 that is in alignment with a sprocket 34, of 50 less diameter, secured to the sleeve 35 that is rotatably mounted on a stub shaft 36 secured to one of the pedestals 11. Also secured to the sleeve 35 is a gear 37 of any suitable pitch and diameter that meshes with and 55 drives a gear 38 similar in pitch and diameter and secured on a shaft 39 mounted in suitable bearings in the pedestals 11. Secured to the shaft 39 and engaging with the endless conveyor is a sprocket 40. At the 60 other end of the conveyor and engaging therewith is an idler sprocket 41 secured to a shaft 42 rotatably mounted in bearings in the pedestals 23. The relation between 65 the driving mechanism above described and connecting the driving shaft 13 with the

shaft 39 is such that the surface speed of the endless conveyor is equal to the surface speed of the elements 22 on the arms 18. Also, the length of the inner reach of the conveyor is less than the arcuate distance between adjacent sets of members 22 so that there is an interval in which the members 22 are not in engagement or associated with the rolls 31. This interval of time during 70 which the elements 22 and 31 are not in engagement is sufficient to allow the operator to shift the position of the hide or skin 32 on the conveyor.

Secured to each of the pedestals 23 on the outside faces thereof and extending forwardly and upwardly are bracket members 43, and to the upper ends of these bracket members are secured the rounded ends of an apron or platform 44 which extends around the front end of the frame members 24, and at its rear end is secured a bracket member 45 secured to, and extending upwardly and forwardly from, the pedestals 11. Secured to or formed on the front face of the pedestals 23 are bearing members 46, these members being in alignment with each other, and secured in such members is a shaft 47. Rotatably mounted on said shaft and extending between the pedestals 23 is a hub 48. Secured to or formed integral with the hub member and extending upwardly therefrom is a member 49, the upper end of which is rounded at 50 and adapted to engage with the front face of the apron 44 for the purpose of holding the sheet of leather 32 80 against the tension exerted thereon by the co-acting members 22 and 31. Also formed integral with the hub 48 and extending downwardly therefrom is an arm 51, the arm 51 and member 49 forming substantially a 85 lever that is pivotally mounted intermediate its ends. Pivotally attached to the lower end of the arm 51 is a connecting rod 52 which, in turn, is pivotally attached to the lower end of the lever 53. The lever 53 is pivotally mounted, intermediate its ends, on a shaft 54 on one of the pedestals 11 and at its upper end has rotatably mounted a roll 55. The roll 55 is adapted to engage with cams 56 formed on a cam disc 57 secured to the shaft 13. Attached to the rear end of the connecting rod 52 is one end of a coil spring 59, the other end of this coil spring being attached to a pin 60 on one of the pedestals 11. The cams 56 are equal in number to the sets of members 22 and bear such relation to the members 22 that the roller 55 is only in engagement with the cams 56 when the members 22 engage with the rollers 31 on the endless conveyor, thus acting to hold the leather 32 firmly in position during the time the elements 22 and 31 act on the leather.

The operation of my improved apparatus 125 is as follows, it being assumed that it is de- 130

sired to perform on a stiff or non-flexible sheet of leather the operation known as staking and preparatory to, for example, the glazing or boarding operation. The operator throws the driving belt (not shown) from the loose pulley 15 onto the tight pulley 14, thus causing a rotation of the shaft 13. Through the mechanism above described, the endless conveyor moves at the same surface speed as the periphery of the circular member carried by the shaft 13 and the groups of members 22 are brought successively into engagement with consecutive rolls 31. Assuming the apparatus to be in a position indicated in Fig. 1 with the circular member rotating in the direction of the arrow shown, the operator places on the apron 44 a sheet of leather, sliding the same under the rounded end 50 of the member 49. The group of members 22 that is shown in engagement with the roller 31 move to the right, as shown in such Fig. 1, and gradually the other member 31 shown to the right hand end of such figure is gradually brought around into position to be engaged by the next succeeding group of members 22. As the members 22 come into engagement with the roller 31 as shown, for example, in Figs. 1 and 3, it will be noted that the leather 32 is gripped therebetween. Also, as soon as this association of members 22 and 31 takes place, a cam 56 will engage with the roller 55, moving the lever 53 about its pivot 54 and causing the rounded end 50 to grasp and force the leather sheet 32 against the rounded apron 44 and hold the same against any tension exerted on it by the members 22 and 31. The associated members 22 and 31 will move to the right, as shown in Fig. 1, while the leather 32 remains stationary and the continuous flexing action given to the leather during this operation is sufficient to render the same pliable enough for subsequent operations to be performed thereon. As the associated members 22 and 31 part company at the right hand end of the conveyor, the cam 56 moves out of engagement with the roller 55 and allows the rounded end 50 of the member 49 to move away from the rounded apron 44, thus freeing the leather from any holding action and the operator will have time to shift the position of the leather 32 on the conveyor before the next succeeding pair of members 22 engage with the other roller 31.

While I have necessarily shown and described the preferred embodiment of my invention somewhat in detail, it is to be understood that I may vary the size, shape, and arrangement of parts within wide limits without departing from the spirit of the invention.

Having thus described my invention, what I claim as new is:—

65 1. An improved staking machine comprising

ing a rotatably mounted member, a staking member thereon an endless belt, means for conforming one reach of said belt in an arcuate path parallel to the path of the rotatably mounted member, and a staking member mounted thereon and associated with the rotatably mounted member.

2. An improved staking machine comprising a rotatably mounted member, a staking member thereon an endless belt, means for conforming one reach of said belt in an arcuate path parallel to the path of the rotatably mounted member, a staking member mounted thereon and associated with the rotatably mounted member, and means for moving said cooperating members in the same direction.

3. An improved staking machine comprising a rotatably mounted member, a staking member thereon an endless belt, means for conforming one reach of said belt in an arcuate path parallel to the path of the rotatably mounted member, a staking member mounted thereon and associated with the rotatably mounted member, and means for moving said cooperating members in the same direction simultaneously.

4. An improved staking machine comprising a rotatably mounted member, a staking member thereon an endless belt, means for conforming one reach of said belt in an arcuate path parallel to the path of the rotatably mounted member, a staking member mounted thereon and associated with the rotatably mounted member, and means for moving said cooperating members in the same direction simultaneously and at the same speed.

5. An improved staking machine comprising a base, a work support mounted thereon, means cooperating with said support to hold work in position thereon, an endless belt mounted in said base and having the upper reach thereof extending upward through the work support, means for conforming the upper reach of said belt in an arcuate path parallel to the path of the rotatably mounted member, a plurality of staking members secured to said endless belt, a horizontally mounted shaft, a member secured thereto and rotatable therewith, a plurality of staking members arranged on the periphery of said member and cooperating successively with the staking members on the endless belt, and means for driving said members in the same direction and at the same speed.

6. An improved staking machine, comprising a base, an endless belt mounted thereon and having the upper reach thereof lying in an arcuate path, a plurality of staking members secured to said endless belt at intervals along the length thereof, a rotatably mounted substantially circular member, a plurality of staking members spaced apart and mount-

4
ed on the periphery thereof, the distance between the staking members on the rotatably mounted member being greater than the length of the upper reach of the endless belt, 5 a clamping means associated with the endless belt and operable to hold work in position while being operated on by the staking

members, and means for releasing the clamping means when the staking element on the rotating member has passed beyond the upper reach of the endless conveyor. 10

In testimony whereof, I have signed my name to this specification.

DANA E. HARDING.
